UNITED STATES PATENT OFFICE.

MARGARET E. GRIFFITH, OF PHILADELPHIA, PENNSYLVANIA.

RECEPTACLE.

1,273,480.

Specification of Letters Patent. Patented July 23, 1918.

Application filed October 25, 1915. Serial No. 57,825.

To all whom it may concern:

Be it known that I, MARGARET E. GRIFFITH, a citizen of the United States, residing at Philadelphia, in the county of Philadelphia and State of Pennsylvania, have invented new and useful Improvements in Receptacles, of which the following is a specification.

This invention relates to urinals and has for its primary object to provide a device of this character in which means is provided for readily attaching the same to the wearer and at the same time allowing the wearer to assume various positions such as when confined to a bed.

Another object of the invention is to so shape the neck portion of the device that the same will conform to the curvature of the body of the wearer at the point of attachment for preventing the passing outwardly of sound waves created within the device.

A further object of the invention is to provide the device with an enlarged body portion adapted to receive the initial discharge of urine and to also provide the same with an outlet pipe by means of which the body portion may be drained of its contents when considered advisable.

With these and other objects in view the invention consists of certain novel features of construction and combination of parts as hereinafter set forth and pointed out in the claim.

35 In the drawings:—

Figure 1 is an elevation of the device showing a portion of the body of the wearer in dotted lines.

Fig. 2 is a longitudinal section thereof. 40 In the drawings the numeral 1 designates the body of a capacity great enough to hold the discharge from the wearer. This body 1 is made of waterproof material and has formed at one end portion a neck 2. This neck 2 flares outwardly toward its edge portion 3. This edge portion 3 is in the form of a bead and has formed integral therewith rings 4 for a purpose hereinafter described.

50 Referring to Fig. 1 in the drawings it will be seen that this edge portion 3 conforms to the curvature of the body of the wearer at the point of attachment so as to

accomplish a perfectly tight set for preventing the passing therearound of liquid or sound waves generated within the body 1 for obvious reasons. At a point of connection of the neck with the body I provide a band 5 that forms a reinforce 55 ment and also supports a ring 6 by means of which the device as a whole may be hung up. For attaching the body to the wearer I have provided straps 7 provided at each end with a snap hook 8 engaging the rings of the bead. At this point attention 60 is called to the fact that when the strap 7 is tight the edge portion of the neck will be brought into tight engagement with the body of the wearer due to the fact of the relative arrangement between the strap and the neck. 65 For draining the body 1 when deemed necessary I have provided an outlet pipe 9 adapted to convey the liquid to any suitable receptacle. It is understood that the pipe 9 can be valve controlled for allowing 70 the body 1 to receive a pre-determined quantity of liquid before the body 1 is discharged.

Having described my invention what I claim is:—

In a device of the character described, in combination a flat-sided bag of waterproof material formed at one end with a neck, said neck being substantially round in curvature flaring outwardly from said bag and having its edge cut away so as to provide a pair 80 of opposed concave edges forming a pair of convex edges at right angles to the concave edges, an integral flexible bead extending completely around the convex and concave edges of said neck to reinforce the 85 same, a pair of rings secured at diametrically-opposite points of said neck upon the upper ends of the said convex edges of said neck, a single adjustable belt having its opposite ends secured to said rings so as to 90 permit either of the concave edges of said neck to be engaged with the body of the wearer and a reinforcing device extending around the bag below the neck, and a supporting device secured thereto. 95 100

In testimony whereof I affix my signature in presence of two witnesses.

MARGARET E. GRIFFITH.
